UNITED STATES PATENT OFFICE.

MAX STEIN, OF CHICAGO, ILLINOIS.

MUSICAL INSTRUMENT.

Application filed December 9, 1926. Serial No. 153,516.

The invention relates to musical instruments and more specially it relates to instruments commonly known as bird organs, such instruments being used for imitating the voice of singing birds, and also being used to teach young birds, for instance, young canary birds to sing. Apparatus of this type heretofore in use were mostly actuated and operated by water-power. In many cases the modulation of the tune, that means the actual singing and trilling of the bird was also imitated by means of water. The apparatus, had the big disadvantage that they did take up too much space, that the water during the operation of such an apparatus would splash and wet the floor of the room wherein said apparatus was located, and finally such apparatus was relatively expensive. All these disadvantages are consequences of the construction of the apparatus known heretofore, and the object of the present invention is to provide an organ to teach young birds to sing and for imitating the singing voice and the melodies of singing birds, avoiding all the above named disadvantages of apparatus used for such purposes heretofore.

A further object of the invention is to provide an apparatus of the above named type which is driven by any suitable motor, but which is actuated by compressed air.

A further object of the invention is to provide an apparatus of the type mentioned, the construction whereof will make it possible to produce the apparatus at a relatively low cost.

A further object of the invention is to provide an apparatus of the class mentioned occupying a relatively small space.

A still further object of the invention is to provide an apparatus of the type mentioned producing the intended results without the use of any medium or means which could in any way interfere with the use, for any other purposes, of the room in which the apparatus is located.

Other objects of the invention not specifically mentioned will be clearly and easily understood and ascertained from the following description in connection with the accompanying drawings forming a part of said description.

It is, however, to be understood that the present invention is not to be restricted or limited to the exact construction described

in the specification and shown in the drawings, but that such changes and alterations may be made as fall into the scope of the claims appended hereto.

In the drawings illustrating a preferred embodiment of the invention Fig. 1 is a front view of the apparatus whereby a part of the casing surrounding the apparatus is omitted.

Fig. 2 is a top view of Fig. 1.

Fig. 3 is a section on line 3—3 of Fig. 1.

Fig. 4 is a view showing a portion of the apparatus in parallel perspective, and Fig. 5 is a section taken on line 5—5 of Fig. 1 whereby the bellows have been removed entirely.

As stated above the present invention is mainly used to teach young canary birds to sing. In order to make it possible to automatically imitate the singing of a good canary bird it is necessary to study the natural singing of such a bird, and close observation and study will teach that the bird will start, or so to say preface its song with some sounds which really cannot be called singing, but in order to teach the young bird it is necessary to follow nature exactly, and to imitate said sounds also. For this purpose the apparatus according to the present invention is equipped with a device to produce these starting sounds, and this device shall herein be called a rattle. The rattle is shown best in Fig. 1. The rattle 5 consists of a bottom plate 6, a back wall 7 and two triangular walls 8. These walls may be made from wood of any suitable kind and thickness. The box thus formed by the walls named is closed by a thin plate 9 extending from the outer edge of the bottom plate 6 to the upper edge of the back wall 7 and connecting the two side walls 8 with each other. This inclined front wall is really to be considered a diaphragm.

Near the upper edge of said diaphragm and approximately about the vertical center line of said front wall 9 an opening 10 is provided above said opening, that means between the upper edge of the opening and the upper edge of the diaphragm a spring 11 is fastened to said diaphragm in any suitable manner, for instance by means of a clamp 12. A wooden block 13 or the like is fastened to the under side of the spring 11 in such a manner that the wooden block 13 is located directly above the opening 10 so that said opening is normally closed by said wooden

block. To the lower end of the spring 11 a weight 14 is fastened. This weight 11 serves a double purpose. For one thing it helps the spring 11 to force the wooden block 13 against the diaphragm 9 in order to close the opening 10. The second purpose of the weight 14 is to rattle against the diaphragm and to produce thereby a sound which exactly imitates the introductory notes produced by a canary bird before starting its actual song. This rattling device is operated in the following manner.

A bellows 15 is provided, the actuation whereof shall be described later. This bellows discharges the air taken in by its upward movement and expelled by its downward movement into a so-called air box 16, through a connecting pipe 79 leading from the bottom of the bellows to said box. A pipe 17 leads from this air box 16 to the rattle 5 and discharges air expelled from the bellows into the rattle at 18. The air forced into the inside of the rattle will escape through the opening 10 and will thereby lift the block 13 from said opening by forcing the spring 11 outwardly. As soon as the air pressure in the rattle will be diminished, the spring will move the block back into its normal position, thereby closing the opening 10 again. This back and forth movement of the block will be repeated in short intervals as long as air is discharged into the rattle. During the back and forth movement of the wooden block 13 the little weight 14 at the end of the spring 11 will hammer against the diaphragm 9 and will thereby, produce the desired sound effect.

In order to limit the time during which this starting sound is produced a certain device is provided which is to be described later.

In order to take in air the bellows have to be lifted, and this may be effected in different ways. In the embodiment shown in the drawing the bellows 15 are inclosed in a box or a frame having a base plate 19, two up-right walls 20 and 21 respectively, and a top plate 22. The rattle 5 is fastened to a part of the base plate 19 extending beyond the vertical plate 20 a lever 23 is pivotally mounted at 24. Said lever has at each end a cam surface 26 and 27 respectively. If the bellows are lifted, either in the way to be described later or in another suitable way, the upper plate 28 of said bellows made of iron or another heavy metal, will engage the cam surface 26 on the upper end of the lever 23 and will force this end of the lever toward the inner side of the vertical plate 20. Said vertical plate 20 is provided, adjacent the upper end of the lever 23, with an opening 29, and a pin 30 pivotally mounted at 31 on the lever 23, extends through said hole. A contact 32 is mounted on the outer end of the pin 30, and an insula-

tion plate 33 is provided between said contact and the pin. On the outside of the up-right plate 20 an insulation plate 34 is fastened carrying another contact 35. The two contacts 32 and 35 respectively are adapted to open and close an electric circuit 36 in which an electric motor (not shown) is arranged. This motor is adapted to drive a pulley 37 mounted on a shaft 38 which is rotatably mounted on top of the plate 22 of the housing for the bellows. A second pulley 39 is mounted on the shaft 38 and the ribbon 40, or a belt or the like is fastened at one of its ends to said pulley and on the other end in any suitable way to the upper plate 28 of the bellows. The upper plate carries, preferably in its center, a rod 41 extending upwardly from said plate and through a hole 42 in the upper plate 22 of the housing for the bellows. This arrangement prevents the bellows from wobbling sideways or cross ways during the movement of said bellows.

In Fig. 1 the contacts 32 and 35 are shown in open position, so that the motor would be deenergized. The weight of the top plate 28 of the bellows is forcing said bellows downwardly and forcing the air out of said bellows through the pipe 79 into the air box 16. This air box has a main channel 80 into which the air flows, which is forced from the bellows through the pipe 79. The different connections from this main channel 80 shall be described later.

When all the air is expelled from the bellows and the top plate 28 of said bellows is nearly on the end of its downward movement, said top plate will engage the cam surface 27 at the lower end of the lever 23 and will force this end outwardly, that means toward the up-right plate 20 thereby moving the upper end of the lever 23 inwardly, so that the pin 30 will be moved through the hole 29, and the contact 32 will engage the contact 35, thereby closing the circuit 36 and energizing the motor which is not shown, whereby the pulley 37 will be driven in such a manner that the belt 40 will be wound up on the pulley 39. In this manner the bellows will be extended and will of course take in air. As soon as the bellows are extended practically entirely, the top plate 28 will engage the cam surface 26 on the upper end of lever 23 and will move away from the contact 35, and the circuit 36 will be broken. Thereby the motor, which is not shown, will be deenergized, so that the bellows can again be forced downwardly by the weight of the top plate 28.

After the starting sound has been produced, the actual singing of the bird should be imitated. The song of the canary bird consists substantially in two parts, one is an even modulation of the tune, that means simply a changing of the notes just like in

any other musical production. The other part is the trilling of the bird, and this trilling is the hardest portion to imitate. In the devices for imitating the singing of a 5 canary, known heretofore, the trilling has been reproduced by the action of water. In most cases air was forced through the water giving a pretty good imitation of the trilling of the bird. To do away with the use of 10 water and of the disadvantages connected therewith a device is provided which shall be called a trembler. A drum 43 of thin wood or the like is rotatably suspended in the following manner: A short pipe 44 15 penetrates the side wall 45 of the drum and is fastened therein. Said short pipe is inserted in the up-right wall 21 of the housing for the bellows, the outer end of the short pipe is surrounded by a cap 46 fastened to 20 said up-right wall and a pipe 47 connects the interior of said cap with the main channel 80 of the air box 16, so that air from said box can enter through the pipe 47 into the trembler. It is to be noted that the axis 25 of the pipe 44 coincides with the axis of the drum. The outer end of this short pipe 48 is rotatably journaled in a cap 50 fastened to and carried by a pipe 51. In this manner the drum is rotatably supported by the up- 30 right wall 21 and the pipe 51. The air which is pressed by the bellows into the main channel 80 of the air box will travel, under certain conditions, which will be described later, through the second channel 35 81 communicating with the main channel 80 and the pipe 47, through said pipe 47 into the drum, and out of the drum through the pipes 48 and 51. The pipe 51 communicates with the channel 82 traversing the air box 40 16, and conducting the air through a short pipe 83 into the whistle 52 which is shown best in Fig. 3. This is a so-called modulation whistle of well-known construction. It is not necessary to describe this whistle 45 in detail because such whistles are not new and said whistle does not constitute a part of the present invention. The manner in which the modulation portion of this whistle will be actuated shall be described 50 later. Whenever air will be driven through the drum into the whistle the singing of the bird will be imitated.

In order to bring about the reproduction of the trilling during the singing the drum 55 is provided with an interior wall 53 and this wall extends from the side wall 45 of the drum to the other side wall 49, thereby dividing the drum into two portions 54 and 55, respectively. The intake pipe 44 communicates with the drum portion 55, and the outlet pipe with the drum portion 54. The connection between the two drum portions is obtained by means of an opening 56 in the interior wall 53. On the upper surface of 60 said interior wall a spring 57 is fastened in

a similar way as the spring 11 is fastened to the outer wall 9 of the rattle 5. A small wooden block 58 corresponding to the wooden block 13 of the rattle is arranged in such a manner as to cover and close the 65 opening 56 when the drum is positioned as shown in Fig. 1. On the outer end of spring 57 a weight 59 is fastened pressing the block 58 down upon the interior wall 53, and helping the spring 57 to close the hole 56. On 70 the side wall 45 of the drum a pin 60 is provided adjacent the circumference of the drum. A bell crank 61 is pivotally mounted at 62 on the upright wall of the housing of the bellows. The downwardly extending 75 arm of the bell crank 61 is forked. Said fork straddles the pin 60. A cam 63 is fastened to the shaft 38 and is positioned thereon in such a manner, that during rotation of the shaft the cam 63 will engage the horizontal 80 arm of the bell crank 61. It is apparent that when the cam 63 engages said bell crank the latter will be pivoted about the pin 62 and will thereby impart a rotary movement 85 to the drum 43. During this movement the 90 drum will get into a position where the weight 59 will not be located any more on top of the divided wall 53 but will be located partly beneath said inner wall so that the weight will pull the block 58 away from 95 the opening 56 thereby permitting the air entering the drum through the pipe 44 to pass freely through said hole and into the pipe 51 and the modulation whistle 52. During the time that the block 58 rests on the 100 interior wall 53 and closes the hole 56 the air pressure will lift the block 58 from said hole in short intervals, so that short blasts of air will pass through said hole in very short time intervals, whereby the whistle 105 will be actuated at shortly interrupted times and thereby the trilling sound intended is produced. The lower arm of the bell crank 61 is made somewhat longer and heavier than the horizontal arm thereof, so that the 110 vertical arm tends to point downwardly whereby the drum will be positioned as shown in Fig. 1, when the horizontal arm of the bell crank is disengaged from the cam 63. The connection between the air box 16 and 115 the rattle 5, as well as the connection between the drum 43 and the air box has to be opened and closed at predetermined times and for predetermined periods. For this purpose the air box is constructed in the 120 following manner: The box really consists of the wooden block 16 in which different passages are drilled. The main passage 80 receives the end of the pipe 79 conducting the air from the bellows to the air box and 125 this passage is then connected with three distributing passages. One of said passages 84 communicates with the end of the pipe 17 connecting the air box with the rattle 5; another passage 81 communicates as 130

stated above with the pipe 47 conducting the air from the box to the drum and the third passage 85 communicates with a short pipe 86 conducting air from the air box to the final whistle 64, the purpose whereof shall be described later. Each one of these three channels distributing air from the main channel is controlled by a valve permitting air to pass into said connecting pipes, when 10 said valves are opened at certain predetermined times and for predetermined periods. Said valves are to be constructed alike, the description of one of these valves will suffice. One of said valves is shown in Fig. 3. 15 It consists of a spring blade 65 pressing upwardly and carrying a thin leather bolster or the like which is forced upwardly by the spring to close the mouth of the respective channel, thereby interrupting the flow of the 20 air through said channel. On the wooden box encasing the whole apparatus three spring hangers 67 are fastened which carry on the circular shaped ends push rods 68. Said push rods extend into the air box 16 25 and touch with the lower ends the leather bolster 66. On the shaft 38 a cam 69 is fastened and said cam will, during the rotation of the shaft 38, engage one of the hangers 67 thereby pushing down the corresponding 30 push rods 68 and opening the valve belonging thereto. This valve controlled by the cam 69 permits air to pass into the drum and from the drum into the modulation whistle, so that this cam really controls the actual 35 singing part of the apparatus. A second cam 70 is fastened also to the shaft 38 and actuates in the same manner as the cam 69, another valve of the type described. This valve controls the flow of the air to the rattle. It is easily understood that whenever 40 the cam 70 engages the push rod pertaining thereto and opens thereby the corresponding valve, air will be permitted to enter the rattle and actuate the same. As soon as the cam 70 disengages the push rod, the valve 45 will be closed, the passage of air will be interrupted and the rattle will be quiet. The third distributing passage controlled by the same type of valve is connected as stated 50 above with a so-called final whistle. This whistle is used to imitate the last notes or tunes of the song of a bird. Observation will teach that a bird will finish its song by repeating the same tune three or four times. 55 For this purpose a third cam 71 is mounted on the shaft 38 and will engage one of the push rods 68 three or four times in succession opening the valve in short intervals, which governs the flow of air to the final 60 whistle 64.

In order to bring about the imitation of the song of the bird the modulation whistle 52 of well-known construction is to be manipulated. The modulation part 73 is to be moved up and down thereby shortening or

lengthening the air columns in the inside of the whistle and producing the different modulations of the song. This up and down movement is obtained in the following manner: A bracket 74 is fastened to the top 70 plate 22 of the housing of the bellows and extends high enough above the shaft 38 to permit the different cams to pass underneath said bracket. On the end of the bracket an arm 75 is pivotally mounted, which carries 75 adjacent its end a second movable arm 76. This arm in turn carries the modulation part 73 of the whistle by means of a cord or cable 77. A modulation cam 78 is mounted on the shaft 38 and engages the arm 75, 80 moving said arm up and down while rotating with the shaft 38. This second arm 76 serves only to adjust the key in which this melody will be reproduced.

The above description shows plainly, that 85 the apparatus according to the invention is adapted to reproduce the song of a canary bird or for that matter of any other song bird by inserting a corresponding modulation cam. The cams as well as the whole 90 apparatus can be easily and cheaply manufactured. A very small motor will serve to drive the apparatus, respectively lift the bellows so that a very efficient device of the desired class is provided at a comparatively 95 low price.

What I claim as new and desire to secure by Letters Patent is:

1. In a device of the class described a bellows, means for expanding said bellows, a weight on top of the bellows for expelling the air taken in, a whistle, a pipe connecting the bellows with the whistle, a drum inserted in said pipe and rotatably mounted, an interior wall in said drum dividing it in two 100 separate chambers, the one portion of the pipe communicating with the one chamber, and the other portion of the pipe communicating with the other chamber, an opening in said interior wall permitting the air from 105 the bellows to pass from one chamber of the drum to the other, a spring fastened to the interior wall, means on said spring for closing the opening in the wall, and a weight on said spring normally forcing said means 110 onto the interior wall for closing said opening, said weight being adapted to remove said closure means from the opening during a certain portion of the rotation of the drum.

2. In a device of the class described a bellows adapted to take in air and expel the same, a rattle consisting of a closed box, a pipe leading the air expelled by the bellows into said rattle, one of the walls of the box 115 having an opening therein, a spring fastened to said wall, a closure block carried by said spring and adapted to close said opening and a hammer on the free end of the spring, the air forced into the rattle being adapted 120

to lift the closure block from the opening and the weight of the hammer and the tension of the spring forcing said block back into closing position and bringing the hammer into contact with said wall of the box.

3. In a device of the class described a bellows, means for expanding said bellows, said bellows being adapted to collapse under the pressure of its own weight, a shaft driving in one direction by the means for expanding the bellows and rotated in the other direction by the weight of the bellows, a rattle, a modulation whistle and a second whistle, a control box, a pipe leading from the bellows to the control box, a second pipe leading from the control box to the rattle, a valve controlling the admission of the air from the control box into the pipe leading to the rattle, means controlled by the rotation of the shaft for regulating the opening and closing of said valve, another pipe leading from the control box to the second whistle, a valve controlling the entrance of air in said last named pipe and means controlled by rotation of the shaft for opening

said valve at predeterminate times, a third pipe leading from the control box to the modulation whistle, a drum inserted in said last named pipe, said drum being rotatably mounted, means for controlling the flow of air through said drum, means controlled by the rotation of the shaft for imparting at predeterminate times, a partial rotation to said drum, and a valve controlled by the rotation of said shaft and controlling the admission of air to the drum.

4. In a device of the class described a bellows, a modulation whistle, a pipe connecting said whistle with said bellows, a shaft adapted to be rotated by the movement of the bellows, a cam on said shaft, an arm pivotally mounted and supporting the extensible portion of the modulation whistle, said arm resting on said cam and said arm and said portion being adapted to be lifted and lowered by the rotation of said cam.

Witness whereof I affix hereto my signature.

MAX STEIN.
